LIQUID DISPENSER FOR VEHICLE WINDSHIELD CLEANING

Robert B. Koch, 7055 Fenkel Ave., Detroit, Mich.

Filed Apr. 15, 1960, Ser. No. 60,213

Term of patent 14 years

(Cl. D58—17)

FIG. 1 is a front elevational view of a liquid dispenser for vehicle windshield cleaning showing my new design;
FIG. 2 is a rear elevational view of the same;
FIG. 3 is a top plan view of the same;
FIG. 4 is a bottom plan view of the same;
FIG. 5 is a side elevational view of the same; and
FIG. 6 is a fragmentary vertical sectional view taken through the line 6—6 of FIG. 1.

I claim:

The ornamental design for a liquid dispenser for vehicle windshield cleaning, as shown.
